UNITED STATES PATENT OFFICE.

SIDNEY M. ISRAEL, OF RICHMOND HILL, NEW YORK.

DESIGN FOR A FRAME RING FOR ELECTRIC LAMPS.

Application filed October 6, 1921. Serial No. 505,945. Term of patent 3½ years.

To all whom it may concern:

Be it known that I, SIDNEY M. ISRAEL, a citizen of the United States, residing at Richmond Hill, county of Queens, and State of New York, have invented a new, original, and ornamental design for Frame Rings for Electric Lamps, of which the following is a specification, reference being had to the accompanying drawing, forming part thereof.

The figure is a perspective view of a frame ring for electric lamps, etc., showing my new design.

I claim:

The ornamental design for a frame ring for electric lamps, etc., as shown.

SIDNEY M. ISRAEL.
